CHARLES F. LEFEVER, OF SYRACUSE, NEW YORK, ASSIGNOR OF ONE-HALF
TO DANIEL M. LEFEVER, OF SYRACUSE, NEW YORK.

BREAKDOWN GUN

SPECIFICATION forming part of Letters Patent No. 732,420, dated June 30, 1903.

Application filed April 13, 1901. Serial No. 55,660. (No model.)

To all whom it may concern.

Be it known that I, CHARLES F. LEFEVER, of Syracuse, in the county of Onondaga, in the State of New York, have invented new and useful Improvements in Breakdown Guns, of which the following, taken in connection with the accompanying drawings, is a full, clear, and exact description.

This invention relates to improvements in breakdown guns, having more particular reference to the means for extracting and ejecting the cartridge.

The object of this invention is to mount the cocking mechanism for the hammer entirely upon the trigger-plate of the gun and to utilize said cocking mechanism for operating the extractor-bar both for the purpose of starting the shell from the barrel and also to return the extractor-bar to its normal inoperative position.

A further object of this invention is to provide a spring-actuated ejector operating upon the extractor-bar and controlled by the hammer of the gun for the purpose of forcibly ejecting the cartridge during the breaking of the gun and only after the cartridge has been fired.

To this end the invention consists in the combination, construction, and arrangement of the parts of a breech-loading firearm, as hereinafter fully described, and pointed out in the claims.

Referring to the drawings, Figures 1 and 2 are side elevations of portions of a gun embodying my invention, the frame and barrel being shown in dotted lines and the gun being shown as broken in Fig. 2. Fig. 3 is a top plan view of the parts seen in Fig. 1. Fig. 4 is a top plan view of the mechanism carried by the trigger-plate, showing particularly the hammers, cocking-lever, sears, and the springs for actuating the hammer and sears. Figs. 5, 6, 7, and 8 are isometric perspective views, respectively, of the detached cocking-lever, one of the hammers, one of the ejectors, and one of the detents for the ejector. Fig. 9 is a detail view of one end of the sliding bar, the adjacent pawl for controlling the movement of the sliding bar and the forwardly-extending arm of the hammer acting upon the pawl.

Similar reference characters indicate corresponding parts in all the views.

As shown in the drawings, the mechanisms of my invention are supported within a suitable gun-frame 1, a barrel 2, a fore-end piece 3, and a trigger-plate 4, the fore-end piece 3 being, as usual, carried by the barrel and detachably secured thereto, and the trigger-plate 4 forming a part of the gun-frame and being also removably secured to said frame.

Carried by the frame 1 are hammers 5, a cocking-lever 6, a sear 7 for the hammers, a mainspring 8, arranged to actuate both hammer and sear, a sliding member 9, adapted to be engaged by the hammer, and a pawl 10 for holding the said sliding member in its operative position.

Mounted upon the barrels or carried thereby are independently-operating extractor-bars 11, an ejector-hammer 12 for each extractor-bar, and independent detents 13 for each of the ejector-hammers, said ejector-hammers being forced to their operative position by suitable springs 14 and the detents 13 being also forced to their operative position by suitable springs 15.

The gun-frame may be of any desired form or size and is so constructed as to receive the various parts of my invention mounted therein and to permit their free operation. The hammer 5, cocking-lever 6, sear 7, and spring 8 are preferably mounted upon the trigger-plate 4, the hammer 5 being pivotally secured to upwardly-projecting lugs or ears 16 upon the trigger-plate and is provided with a forwardly-extending arm 17, having a curved upper bearing-face and a lower concave face, the upper curved face being adapted to engage the pawl 10 for forcing the same to its inoperative position, and thereby releasing the sliding bar 9 as the main hammer reaches its cocked position, and the lower engaging face of said arm being engaged by a suitable shoulder or member 18 upon the cocking-lever 6, so that when the forward end of the cocking-lever is elevated the member 18 will engage the arm 17 and rock said main hammer to its cocked position, said hammer being provided with an engaging shoulder 19, which automatically interlocks with the adjacent end of the sear 7,

which sear serves to hold the hammer in its cocked position until released by one of the triggers, as 30, of the gun. This hammer 5 is also provided with an engaging shoulder 19, rising from the rear end of the upper curved surface of the arm 17, for the purpose of engaging the rear end of the sliding bar 9 and forcing said sliding bar to its operative position when the hammer is fired, as indicated in Fig. 1 and for a purpose hereinafter described. The cocking-lever 6 is also pivotally mounted upon the intermediate upwardly-projecting ears 16 of the trigger-plate at a point above and at the rear of the pivotal pins 22 of the hammer 5, said cocking-lever being extended downwardly and forwardly beyond the pivotal pins 22 and preferably extends a sufficient distance forward to engage the intermediate portion of the extractor-bars 11, said cocking-lever being provided with an upturned hook-shaped extremity 23, having a cut-out 24 in its rear face for receiving a cocking member or roller 25, which is secured to the lug 26 of the barrel 2 and serves to limit the rocking movement of the barrel on the frame when the gun is broken. The upper end of the extension 23 of the cocking-lever preferably extends into a suitable recess 27, formed in the lower faces of the extractor-bars 11, being adapted to engage the opposite end walls or shoulders of said recess 27 for moving the extractor-bars 11 rearwardly and forwardly as the gun is broken and closed. When the gun is broken, the cocking member 25 interlocks with the walls of the recess or cut-out 24, thereby rocking the cocking-lever upwardly upon its pivot 28 and forcing the shoulder or member 18 into engagement with the lower face of the forwardly-extending arm 17 of the hammer 5, which, it is apparent, rocks the hammer rearwardly upon its pivot 22 with a gradually-increasing leverage until the shoulder 19 is aligned with the front end of the sear 7, said sear being automatically forced into engagement with said shoulder by one arm of the spring 8, the other arm of said spring serving to force the hammer to its operative position when the sear is withdrawn from engagement with said hammer.

The shoulder or member 18 preferably consists of a roller mounted upon a suitable spindle and serves to reduce the friction between the arm 17 and the member 18, also causing said parts to move more freely one upon the other. The cocking member 25 is also provided with a roller for the same purpose, (of reducing the friction,) and it is evident that these rollers reduce to a minimum the wear of the parts in contact therewith.

It is evident from the foregoing description that as the gun is broken the extension 23 of the cocking-lever 6 engages the rear wall of the cut-out 27 of the extractor-bar, and therefore positively moves the extractor-bar a limited distance outwardly, and that when the

gun is closed the opposite face of the extension 23 engages the front wall of the cut-out 27 and positively returns the extractor-bar to its normal position.

It is sometimes desirable to vary the throw of the sear 7—that is, to cause the sear to engage more or less of the hammer—and I therefore provide a suitable adjusting-screw 30, movable in a threaded aperture in the frame, or, rather, in the trigger-plate, by which the end of the sear adjacent to the engaging shoulder 19 may be made to engage more or less of said shoulder 19, as desired.

The sliding bar or member 9 is mounted in the frame of the gun, is movable lengthwise thereof, and is provided at its rear end with an engaging shoulder 31 and a depression 32, the shoulder 31 being engaged by the pawl 10 when the hammer 5 has forced said sliding bar forwardly to the limit of its movement, and the pawl 10 is automatically forced to its operative position for engaging said shoulder 31 by a spring 33, interposed between the upper end of the pawl 10 and the adjacent portion of the frame. This sliding member is adapted to operate in conjunction with the ejector-hammers, there being one of these bars for each hammer, and each is actuated independently of the other by its corresponding hammer and serves to control the position of its detent 13 with relation to its respective ejector-hammer 12. These ejector-hammers are preferably movable independently of each other, there being one of these hammers for each of the extractor-bars 11, and are pivoted at their lower ends at 34 to the fore-end piece 3, their upper ends being arranged to engage the front ends of the extractor-bars 11, and the front faces of their intermediate portions are provided with shoulders 35 and 36, the shoulders 35 being beneath the shoulders 36 and are engaged by the springs 14, which are normally tensioned to rock the ejector-hammers rearwardly for forcing the extractor-bars outwardly or rearwardly. The shoulders 36 are normally engaged by similar shoulders formed upon the detents 13, which are mounted upon the fore-end piece and are arranged to slide forwardly out of engagement with the shoulders 36. These detents 13 are held in operative engagement with the shoulders 36 by the springs 15, the rear ends of which are engaged with inclined faces 37 upon the forward ends of the detents, said springs serving to ride upon said inclined faces and to normally force the detents rearwardly. The rear ends of these detents are also inclined upwardly and rearwardly and are arranged to engage the forwardly-projecting ends of the sliding bars 9 as the gun is broken, whereby said detents are forced forwardly, the forward faces of said sliding bars being also inclined and are so relatively arranged to the inclined faces 38 of the detents that the detents are moved out of engagement with the shoulders 36 of the ejector-

hammers as the gun reaches the limit of its movement during the operation of breaking the same.

In the operation of my invention when the hammer is fired the sliding bar 9 is thereby forced forwardly, its forward end projecting beyond the front end of the frame, and the pawl 10 automatically interlocks with the shoulder 31 for the purpose of holding said sliding bar in its forward position. When the gun is broken, the inclined face 38 of the detent 13 engages the forward end of the sliding bar 9, and the detent is thereby forced forwardly out of engagement with the shoulder 36 of the ejector, whereupon the spring 14 automatically and forcibly moves the extractor-bar outwardly to withdraw the shell from the barrel. At the same time this operation is taking place the cocking-lever is elevated by the member 25 until the hammer is forced to its cocked position, and when the hammer reaches or, rather, approaches its cocked position the upper curved face of the arm 17 engages the lower face of the pawl 10, thereby elevating said pawl and releasing the sliding bar 9, which is then forced rearwardly by the detent 13, actuated by the spring 15. When the sliding bar has reached the limit of its rearward movement, the pawl 10 automatically drops or is forced into the cut-out 32 and serves to hold said sliding bar from forward movement during the return of the gun to its closed position, it being understood, as previously described, that the extension 23 of the lever 6 engages the opposite walls of the cut-out 27 in the extractor-bars 11 and serves to positively move the extractor-bars a limited distance in reverse directions as the gun is opened and closed.

It is sometimes desirable to prevent the action of the ejector mechanism, and I therefore provide the fore-end piece with an adjusting-screw 39, which is arranged to engage the springs 14 for the purpose of forcing said springs away from the shoulder 35 or, rather, for the purpose of holding said springs from operating against said shoulder and the ejector-hammers.

The detents 13 are guided in suitable openings in the head of the fore-end piece and are also formed with grooves in their upper faces which engage suitable studs depending from the adjacent portion of the fore-end piece, these studs and the openings in the fore-end piece, serving to retain the detents in their proper positions.

Any suitable means may be employed for locking the barrel to the gun-frame; but I preferably employ a transversely-sliding bolt 40, movable in suitable apertures in the frame and arranged to enter an opening 41 in the rearwardly-projecting lug of the barrel 2, and in order to compensate for the wear incidental to the movement of the said sliding bolt upon the walls of the opening 41 I provide a suitable adjusting-screw 42, movable in a threaded aperture in the lower wall of the lug,

which serves not only to take up the wear as just described, but also to maintain a more perfect alinement of the barrels of the gun 70 with the firing-pins.

The operation of my invention will now be readily understood upon reference to the foregoing description and the accompanying drawings, and it will be noted that some change 75 may be made in the detail construction and arrangement of the component parts without departing from the spirit thereof. Therefore I do not limit myself to the precise construction and arrangement shown and described. 80

Having thus fully described my invention, what I claim as new, and desire to secure by Letters Patent, is—

1. In a breakdown gun, the combination with a frame and a barrel, a pivoted hammer, 85 an extractor-bar having a recess, a cocking-lever pivoted to the frame at the rear and above the hammer-pivot and provided with a forward and upward extension projecting into said recess for engaging and moving the 90 extractor in reverse directions, a cocking member carried by the barrel and engaged with the upper and rear faces of said extension, and a shoulder on the lever engaging the hammer in front of its pivot for cocking 95 the hammer.

2. In a breakdown gun, the combination with a frame and a barrel, of a pivoted hammer having a forwardly-projecting arm, an extractor-bar, a cocking member carried by 100 the barrel, a cocking-lever pivoted at its rear end to the frame at one side of the hammer-pivot, and extending forwardly beneath and in front of the cocking member and engaged with said member, the front end of said lever 105 being extended upwardly and engaged with the extractor-bar to move the same in reverse directions as the gun is opened and closed, and a shoulder on the lever engaged with the lower face of the arm of the hammer for cocking 110 the hammer.

3. In a breech-loading gun, the combination with a frame and barrel, of a pivoted hammer having a forwardly-projecting arm, an extractor-bar having a recess, a cocking member 115 on the barrel, and a cocking-lever having one end fulerumed on the frame at the rear of the breech-face and its other end engaged with said member and projecting into the recess, for simultaneously moving the extractor-bar 120 endwise and rocking the lever as the gun is opened and closed, the intermediate portion of the lever having means to engage said arm and cock the hammer as the gun is opened.

4. In a breakdown gun, the combination 125 with a frame and barrel, of a pivoted hammer having a forwardly-projecting arm, an extractor-bar, a spring-actuated ejector-hammer engaged with the end face of the extractor-bar, a detent for the ejector-hammer, means 130 actuated by the firing of the main hammer to trip the detent when the gun is opened, a cocking-lever pivoted at its rear end to the frame and having a hook-shaped forward end engag-

ing the extractor-bar to move the same against the action of the ejector-hammer, a cocking member between the bar and lever and engaged with the hook-shaped end of the lever, and means on the lever engaged with the main hammer to cock the same.

5. In a breech-loading gun, the combination with a frame and barrel, of a pivoted hammer having a forwardly-projecting arm, a cocking-lever fulcrumed on the frame at the rear of the breech-face and above the hammer-pivot and extending forwardly beyond the breech-face and hammer-pivot, said lever having means to engage the arm and cock the hammer as the gun is broken, a cocking member and an extractor-bar both carried by the barrel, and engaged with the front end of the lever for the purpose described.

6. In a breakdown gun, the combination with the frame and barrel, of a spring-actuated ejector-hammer for forcing the shell from the barrel, a detent for the ejector-hammer, means movable into and out of the path of the detent for engaging said detent and forcing the same to its inoperative position as the gun is broken, and a pawl for holding said means in its operative position, a hammer, and an operative relation between the hammer and pawl for operating the latter to release 30 said means and permit the same to return to its inoperative position.

7. A breakdown gun comprising a frame and barrel, a hammer, an ejector-hammer, a sliding bar movable into and out of the path of the detent for the purpose described, said sliding bar being moved forwardly by the firing of the hammer, a pawl for holding said sliding bar in its forward position, and an operative 35 relation between the hammer and pawl for operating the latter to release the sliding bar and permit it to return to its inoperative position.

8. The combination with the frame and barrel of a breech-loading firearm, of an extractor-bar on the barrel, a hammer, a spring-actuated ejector-hammer for forcing the extractor-bar outwardly, a detent for holding the ejector-hammer in its inoperative position, a sliding bar actuated forwardly by the firing of the hammer for forcing its forward end into the path of the detent, whereby when the gun is broken said detent engages the sliding bar and is automatically moved to its inoperative position for releasing the ejector-hammer, a pawl for holding the sliding bar in its forward position and means provided on the hammer for moving the pawl out of engagement with the sliding bar as the hammer is cocked for releasing said sliding member.

9. The combination with the frame and barrel,

rel of a breech-loading gun, of an extractor-bar, a hammer, a spring-actuated ejector-hammer for operating the extractor-bar, a 65 detent for holding the ejector-hammer in its inoperative position, a cocking-lever mounted on the frame, and arranged to engage the extractor-bar for the purpose described, a sliding member movable forwardly into the path of the detent whereby the detent is moved to its inoperative position for releasing the ejector as the gun is broken, a pawl for engaging the sliding member and holding the same in its forward position; and means provided on 70 the hammer for moving the pawl as the hammer is cocked for releasing the sliding member and permitting its rearward movement.

10. In a breakdown gun, the combination with a pivoted hammer, of an extractor-bar, an ejector-hammer and a detent therefor, a cocking-lever pivoted at the rear of the main hammer-pivot and extending forwardly therefrom into a hook-shaped extremity, an engaging shoulder on the lug of the gun-barrel interlocking with said extremity, whereby the cocking-lever limits the opening of the gun, said extremity also moving the extractor-bar endwise in reverse directions as the gun is opened and closed to cock the ejector-hammer as the gun is closed, a shoulder on the cocking-lever in front of the hammer-pivot and engaging the hammer with an increasing leverage as the gun is opened for cocking the hammer, and means actuated by the firing 95 of the hammer to disengage the detent from the ejector-hammer as the gun is opened.

11. In a double-barrel breech-loading gun, the combination with the main hammers, of a shoulder carried by the barrels, a single cocking-lever having one end fulcrumed at the rear of the breech-face, and its other end extended beneath and in front of the shoulder and engaged with its front face whereby the lever is rocked as the gun is opened and closed 105 and means on the intermediate portion of the lever for cocking both hammers.

12. The combination with a pair of hammers having forwardly-projecting arms, of a shoulder carried by the barrels, a single cocking-lever fulcrumed at the rear of the breech-face and extending forwardly beneath and in front of the shoulder to engage its front face, and additional shoulders carried by the intermediate portion of the lever and engaging 110 the lower faces of the arms of the hammers for the purpose described.

In witness whereof I have hereunto set my hand this 6th day of April, 1901.

CHARLES F. LEEFEVER.
